CLAIM

The ornamental design for a foldable sheet having embedded LED lights as shown and described.

DESCRIPTION

FIG. 1 is a perspective view of the foldable sheet having embedded LED lights of the present invention;

FIG. 2 is a front view of the foldable sheet having embedded LED lights shown in FIG. 1;

FIG. 3 is a left side view of the foldable sheet having embedded LED lights shown in FIG. 1;

FIG. 4 is a right side view of the foldable sheet having embedded LED lights shown in FIG. 1;

FIG. 5 is a top end view of the foldable sheet having embedded LED lights shown in FIG. 1; and,

FIG. 6 is a bottom end view of the foldable sheet having embedded LED lights shown in FIG. 1.

The foldable sheet having embedded LED lights is shown with symbolic breaks in its length. The appearance of the portions of the article not shown beyond the break lines forms no part of the claimed design.
